UNITED STATES PATENT OFFICE.

DONALD S. BARROWS, OF ROCHESTER, NEW YORK, ASSIGNOR, BY MESNE ASSIGNMENTS TO THE SYMINGTON COMPANY, A CORPORATION OF MARYLAND.

JOURNAL BOX.

Application filed October 30, 1924. Serial No. 746,796.

The invention relates to journal boxes for railway cars and more particularly to the lid construction for closing the opening through which the journal box is lubricated.

To this end, the principal feature of my invention, generally stated, consists in providing a pivoted lid construction adapted to contact the walls of the journal box opening, together with spring and lever means for maintaining the lid in closed and open positions.

Another object of the invention is to provide an articulated lid construction comprising a pressed metal member adapted to close the journal box opening, a spring member pivotally supported by the hinge pindle, and a lever construction cooperating with the closure member and spring to provide means for maintaining the said closure member in open or closed position.

A still further object of the invention is to provide a simple lid construction, a torsion spring mechanism, and a lever mechanism adapted to engage the lid and box at opposite ends and to coact with the torsion spring to provide means for maintaining the lid in open or closed position.

A still further object of the invention is to provide, in combination with a simple flat lid, a spring mechanism carried by the journal box hinge lug and a lever mechanism operatively interposed between the lid and journal box and adapted to energize said spring, said lever being provided with a hood or cover overlying the intersection of the hinge lug and lid so as to afford protection at these lines of intersection against the entry of water, dirt, etc., into the said journal box.

To these and other ends, the invention consists of the various elements and combinations of elements as hereinafter set forth.

In the drawings:

Figure 1 is a front elevational view of a portion of the lid and associated journal box.

Figure 2 is a cross-sectional view taken substantially on the longitudinal center line of the box, only a portion of the journal box being illustrated.

Figure 3 is a top plan view of the construction shown in Figure 1.

Figure 4 is a view similar to Figure 1 showing a modified form of lever.

Figure 5 is a central vertical sectional view of the construction shown in Figure 4.

Figure 6 is a top plan view of the lever mechanism illustrated in Figures 4 and 5.

Throughout the specification and drawings like parts are designated by like reference characters.

Referring first to the construction illustrated in Figures 1, 2 and 3, the journal box is designated by the reference character 1 and is preferably of the standard A. R. A. construction having on its upper surface 2 and adjacent the forward edge thereof, a hinge lug 3 which is perforated, as at 4, for the passage of the hinge bolt or pindle 5, said lug being provided at the front and top with flat faces 6 and 7, respectively, for cooperation with a portion carried by the lid to maintain the lid in closed and open positions.

Pivotedly connected to the hinge pindle 5, preferably by means of ears or loops 8, and adapted to cover the opening 9 in the front face of the journal box, is the cover or lid 10 which may be, and preferably is, formed from pressed metal, the ears 8 being conveniently formed by bending portions of the lid 10 to form loops surrounding the hinge pindle. Adjacent the hinge lug 3 the lid 10 is cut away, as at 11, the cut-away portion being of slightly greater width than the total width of the hinge lug 3 for a purpose to be herein-after described. The cut-away portion 11 does not extend below the base of the hinge lug, as clearly shown in Figure 2, so that there is no opening into the journal box which is not closed by the lid 10 when the latter is in closed position.

Pivotedly mounted upon the hinge pindle 5, preferably by having loop portions 12, is a torsion spring 13 having a pair of coils 14, the inner ends of said coils being connected by a straight portion 15 of said spring. It will be observed that the spring 13 thus comprises loop portions 12 which engage with the hinge pindle 5 upon opposite sides of the hinge lug 3, and coil portions 14 which are connected at their adjacent ends by an integral portion 15 of said spring. The spring 13 does not engage the lid and, as before stated, is pivotally mounted on the hinge pindle 5.

The numeral 16 designates a lever mechanism of general cruci-form shape. This lever 16 is provided with a bearing face 17 which is adapted to engage the faces 6 or 7 of the hinge lug and at its opposite ends it is provided with

a bearing portion 18 of general spherical form which is adapted to fit within a correspondingly formed recess 19 in the exterior face of the lid 10. Overlying the portion of the lever 16 carrying the bearing 18 there is provided a strap 20 which is connected to the lid 10 and is adapted to prevent the disengagement of the lever and lid under normal conditions. Intermediate the portions 17 and 18 the lever 10 is provided with curved portions 21 adapted to receive the coils 14 from the spring 13 and intermediate the portions 21 there is formed on the lever a curved seat portion 22 which is adapted to receive and coact with the straight portion 15 of the spring 13. Preferably, the lever 16 is provided with a plurality of strengthening ribs 23 connecting the exterior of the curved portions 21 with the outer face of the bearing portion 17 and similarly 20 the lever may be provided with a centrally disposed reinforcing or strengthening rib 24 extending downwardly from the shoulder 22 to and beyond the bearing portion 18. On the interior of the curved faces 21 there are provided 25 curved bearing portions 25 which, when their parts are assembled, as hereinafter noted, engage the outer adjacent portions of the coils 14. The distance from the straight portion 15 of the spring 13 to the center of the hinge pintle 5 is less than the distance from the seat 22 of the lever 16 to the center of the hinge pintle. It therefore follows that when the parts are assembled by sliding the lever 16 downwardly between the spring and the lid 30 35 40 45 50 55 60 65

10, that to permit the parts to be assembled the coil portions 14 of the spring 13 are placed under tension which is only partially relieved by the entry of the portion 15 of the spring into the seat 22. This tension in the spring 13 reacts against the bearing portions 17 and 18 of the said lever 16 and causes the bearing portion 18 to force the lid 10 firmly against the walls surrounding the opening 9 in the journal box. As this pressure is central on the lid and since the ears 8 of the lid are of greater size than the diameter of the hinge pintle 5 it necessarily follows that the lid 10 is adapted to have a limited movement so as to compensate for any irregularity in the surface of the walls surrounding the journal box opening.

In Figures 4, 5 and 6 the construction of the lid 10, the spring 13, and the manner in which the lid and spring are connected to the hinge 5 10 15 20 25 30 35 40 45 50 55 60 65

is identical with that illustrated in Figures 1, 2 and 3. In this construction, however, the lever 16^a instead of being of general cruciform shape is preferably substantially T-shaped, the side portions or arms 26 of the lever not only extending over the coil portions 14—14 of the spring 13 but extending upwardly and then inwardly so as to partially embrace the hinge lug 3 of the journal box, as clearly shown at 27 in Figure 5. By this construction the exposed portion of the lid

10 along the outer face of the hinge lug 3 is housed over so that the entry of dirt and moisture is partially, if not entirely, eliminated. The lower end of the lever 16^a is provided with a pair of lateral ribs 24^a instead of a single centrally arranged rib 24, as in the preceding figures. Except as above noted, the construction of Figures 4 to 6 is identical with the construction of Figures 1 to 3.

The operation of the device is as follows: 75

When the lid is raised, that is moved on the hinge pintle 5, the bearing portion 17 of the lever 16 slides upon the face 6 until the lid and lever are raised to such a position that the bearing portion 17 slides upon and engages 80 the face 7 of the hinge lug whereupon the tension on the spring 13 will maintain the lid in open position until such time as it is forcibly returned to closed position.

It will be observed that the lid construction 85 hereinbefore described and illustrated comprises but three parts of simple construction but of certain and efficient operation.

Having now described my invention, what I claim is:

1. In a device of the character described, the combination with a journal box having a hinge lug thereon, of a lid pivotally connected thereto, a spring member carried by said journal box, and a lever interposed between said box and lid and engaging them adjacent its ends, said lever being adapted to energize said spring by sliding in place between said spring and lid. 90 95

2. In a device of the character described, the combination with a journal box having a hinge lug thereon, of a lid pivotally connected thereto, a spring member pivotally connected to said journal box, and a lever interposed for transmitting force between 100 105 said box and lid, said lever being adapted for insertion between the spring and lid, with one end engaging said box, to energize said spring.

3. In a device of the character described, the combination with a journal box having a hinge lug thereon, of a lid pivotally connected thereto, a torsion spring pivotally mounted on said journal box, and a lever engaging said box and lid, and interposed between said box and lid spring, having a seat 110 115

engaged by said spring and adapted to energize the latter, said engagement between the spring and lever serving to retain the latter in proper position.

4. In a device of the character described, the combination with a journal box having a hinge lug with angularly related faces thereon, of a lid pivotally connected thereto, a spring member carried by said journal box, and a lever interposed between said box and lid, said lever being adapted to contact one or the other of the faces of said hinge lug and lid at its opposite ends to hold the lid in open or closed position, and formed with portions 120 125 130

adapted to partially house the spring member.

5. In a device of the character described, the combination with a journal box having 5 a hinge lug thereon, of a lid pivotally connected directly thereto, said lid having a depressed portion on the outer surface thereof, a spring carried by said journal box and independent of said lid, and a lever interposed 10 between said box and spring, said lever having a convex bearing portion engaging the depressed portion of said lid.

6. In a device of the character described, the combination with a journal box having 15 a hinge lug thereon, of a lid pivotally connected to said box by a hinge pintle, a spring member pivotally mounted on said pintle, and a lever engaging said lid and box at opposite ends, said lever being adapted to energize 20 said spring by being slipped in place between said lid and spring.

7. In a device of the character described, the combination with a journal box having a hinge lug thereon, of a lid pivotally connected to said box by a hinge pintle, a torsion 25 spring member pivotally mounted on said pintle, and a lever engaging said lid and box at opposite ends, said lever being adapted to energize said spring and being provided with 30 a portion partially embracing said hinge lug.

8. The combination with a journal box having a hinge lug thereon with angularly disposed bearing faces, of a lid therefor, a pintle extending through said hinge lug, said 35 lid comprising a plate member hingedly mounted on said pintle, a spring member piv-

otally mounted on said pintle, and a lever arranged exteriorly of said plate member and engaging said plate and one of the bearing faces of the hinge lug at opposite ends to hold 40 the lid in either open or closed position, said lever having a spring seat portion thereon adapted to releasably engage said spring.

9. The combination with a journal box having a hinge lug thereon with angularly disposed bearing faces, of a lid completely closing 45 said journal box opening, a hinge pintle for pivotally connecting said lid and lug, a torsion spring member pivotally mounted on said pintle, and a lever contacting 50 said lid and one of the faces of the lug at opposite ends to hold the lid in open or closed position, and means for operatively connecting said spring and lever.

10. The combination with a journal box 55 having a hinge lug thereon with upper and outer faces, of a lid therefor, said lid comprising a plate member completely closing said journal box opening, a pintle for pivotally connecting said lid and lug, a lever connected to said lid at one end and engaging 60 one of the faces of said lug at the opposite end to hold the lid in open or closed position, said lever having portions overlying the upper face of said lug when the lid is closed, 65 a torsion spring member embracing said lever and pivotally mounted on said pintle, and means for releasably connecting said lever and spring.

In testimony whereof I affix my signature.

DONALD S. BARROWS.
